MINING DRILL AND BIT

Walter Cook, Benton, Ill., assignor to Central
Mine Equipment Co., St. Louis, Mo., a corpo-
ration of Michigan

Application October 30, 1936, Serial No. 108,349

9 Claims. (Cl. 255—69)

This invention relates to mining drills and bits, and has special reference to detachable drill heads and detachable bits therefor designed and adapted specially for use in connection with electric breast drills and hand breast drills and augers, although it will become apparent from the following disclosure that the utility of the invention is not restricted in this particular.

Objects of the invention are to provide an improved detachable drill head having detachable bits in connection therewith that may be made and sold at low cost and that are suitable for either electric or hand breast drilling; to provide bits of novel form and design with wedges for securing them in connection with the drill head in such a manner that the bits deflect the cuttings inwardly and somewhat toward the center of the drill head and prevents the material from offering so much resistance to the person operating the breast drill as do other types of breast drills with which I am familiar; to provide a drill with novel bits that relieve or reduce the pressure required to operate the drill and which apply a pulling-in force or tendency when the drill is operating; to provide novel detachable wedges for cooperating with the novel bits so as to secure the bits in connection with the head so that the bits will feed the material inwardly; to provide bits made of material that is polygonal in cross-section and are bent or curved diagonally or toward one of the corners thereof, and which have oblique or inclined walls at their outer ends forming sharp cutting edges having extended points or corners at their inner sides from which the edges incline rearwardly and outwardly to intersection with the outer edges of the bits; and to provide a novel drill head with detachable bits and wedges in connection therewith, assembled in a novel relationship and providing a drill that is substantially free from vibration when in use.

Another object of the invention is to provide a drill head having bits of novel construction attached thereto causing the cuttings from the material or mineral to flow toward the center of the drill head so that they will move rapidly along the drill without substantial tendency to choke or retard operation of the drill.

Other objects of the invention will be apparent from the following description, reference being made to the annexed drawing, in which—

Fig. 1 is a side elevation of a drill head equipped with my improved bits.

Fig. 2 is a side elevation at right angles to that shown in Fig. 1.

Fig. 3 is an end elevation.

Fig. 4 is an end elevation of the drill head, the bits and the wedges being shown in section at the end of the drill head.

Fig. 5 is a side elevation of a wedge and two bits in connection therewith assembled ready to be driven into the socket in the drill head.

Fig. 6 is a side edge elevation of the wedge and one of the bits in connection therewith.

Fig. 7 is a rear side elevation of one of the bit blanks before it is bent to final shape.

Fig. 8 is a side edge elevation looking toward the righthand side of the blank shown in Fig. 7.

Fig. 9 is a sectional view on the line 9—9 of Fig. 5.

Fig. 10 is an end elevation of a drill head having the sockets therein formed at different angles from the angles of the socket in Fig. 4, the bits and the wedges being shown in section adjacent to the end of the drill head.

Fig. 11 is a sectional view of one of the wedges and the two associated bits of the type shown in Fig. 10 but detached from the drill head.

The invention herein disclosed, in one aspect, is an advance and improvement in reference to the inventions disclosed in my prior application Serial No. 65,054, filed February 21, 1936; and the novel subject matter herein disclosed and claimed attains the new and useful objects, functions and effects stated generally in the preceding part of this specification and now more specifically described.

The detachable drill head 1 shown in Figs. 1 to 4, inclusive, is designed and intended to be attached to the main part of an auger in the manner of the drill head disclosed in my said co-pending application. In the specific construction shown in Figs. 1 to 4, inclusive, the end of the head 1 is provided with two sockets 2 which are inclined relative to the axis of the drill. These sockets incline inwardly from their forward ends toward their rear ends which are open, and also incline forwardly in the direction in which the drill is rotated when in use. These sockets are provided to receive the rear ends of the bits and also to receive wedges whereby the bits are rigidly and detachably attached to the head 1.

As shown in Fig. 4, the front and rear side walls of each of the sockets 2 are approximately parallel, the front walls being spaced a substantial distance apart and substantially outwardly from the axis of the head, which is to say that the front walls of the sockets 2 are angularly disposed to the radii of the head. The outer ends of each of the sockets 2 comprise corners 3 formed by walls 4 converging from the front and

rear walls of said sockets to intersection at and to form said corners 3. Similarly, the inner ends of said sockets 2 comprise corners 5 formed by walls 6 converging from the ends of the side walls 4 of the sockets to intersection at and to form the corners 5.

The bits comprised within the present invention are of novel construction, each being formed from an elongated blank 7 which, in the specific embodiment shown, is substantially square in cross-section and has on its outer end a beveled wall 8 formed on a bias, which is to say that its rear end 9 extends angularly across the front side of the blank 7 and its forward end intersects the rear side of the blank 7 diagonally to form an inclined cutting edge 10. After this blank has been formed, it is bent diagonally into arcuate form in which the corner 11 is the outer wall of the arc and the diagonally opposite corner 12 is the inner wall of the arc. These bits are proportioned and shaped so that, when they are placed in the sockets, one corner of each bit will fit within the corner 3 or within the corner 5 of each socket, and two of the side walls of each bit will seat and wedge against the two walls 4 or against the two walls 6 of each socket, as clearly shown in Fig. 4 of the drawing.

In this embodiment of the invention, the bits are wedged in the sockets by wedges appropriately shaped and formed for that purpose. Each wedge comprises an elongated tapered body 13 having a length greater than the length of any of the sockets 2 so that, when the wedges are driven into the respective sockets, the rear ends of the wedges will extend beyond the rear ends of the sockets and constitute heads 14 adapted to be struck by a hammer or other tool and driven forwardly from the sockets. This implies that the wedges taper rearwardly, as shown.

Each wedge is formed in two of its opposite sides with angular grooves 15 the walls of which grooves constitute seats for the walls of the bits opposite from the walls of said bits which seat against the socket walls 4 and 6, respectively. To permit the wedges to turn properly to tight wedging position in the sockets, the rear walls 16 of said wedges are rounded (Fig. 4) so that, when they seat against the rear walls of the sockets 2, the wedges may turn properly to form the wedging engagement with the respective bits and with the walls of the sockets in which the wedges and bits are clamped.

It will be observed that the beveled walls 4 intersect the rear walls of the bit bodies in such a way as to form the inclined cutting edges 10 having forwardly extended points or corners 17 beyond the remaining portions of the cutting edges. This construction is effected by forming the beveled walls 8 on a bias or inclination, as shown, and bending or curving the bits in a diagonal direction so that the corners 12 are at the front of the bits and the corners 11 are at the rear of the bits.

The head shown in Fig. 10 has sockets 18 therein with their front walls 19 approximately radial. Otherwise, these sockets 18 are formed and shaped like the sockets 2. By forming these sockets 18 in this manner, the two bits toward the center of the head are almost in radial alignment with their respective outer bits; whereas, in the arrangement shown in Fig. 4, the bits nearer the periphery of the head are considerably in advance of the inner bits when the drill is rotating. The arrangement shown in Fig. 10 feeds the cuttings more rapidly toward the axis

of the drill head so that the cuttings will pass through the spaces 20 in the drill head into the spiral structure of the drill head, and thence to the spiral auger.

From the foregoing it should be apparent that this invention attains its intended objects and purposes efficiently, and that such variations in the formation and relationship of the parts are contemplated as may be required to adapt the invention for use in drilling through different substances and minerals. Other variations may be made within the scope of the invention without departure from the nature and principle thereof.

I claim:

1. In a mining drill having a pair of sockets in its forward end each having two side walls and two converging walls at each end forming corners at the inner and outer ends of said sockets, bits extending into said sockets and having corners seated in said corners in said sockets, and wedges having sockets complementary to said corners at the ends of said sockets wedging said bits in said sockets in a relationship in which corners of said bits extend forwardly in the general direction of rotation of the drill, and said bits curving diagonally toward said forwardly extending corners thereof and having diagonally biased walls forming cutting edges on their ends.

2. A bit of the character described comprising an elongated body that is substantially rectangular in cross-section and which curves diagonally leaving one of said corners forming the outer edge of the curved body and a diagonally opposite corner forming the inner curved edge of said body, and said body having a diagonally biased beveled wall at its forward end extending from its forward side to intersection with its rear side and forming a sharp cutting edge.

3. A bit of the character described comprising an elongated body that is substantially rectangular in cross-section and which curves diagonally leaving one of said corners forming the outer edge of the curved body and a diagonally opposite corner forming the inner curved edge of said body, and said body having a diagonally biased beveled wall at its forward end extending to intersection with the side of the bit between the outer and rear corners and forming a sharp cutting edge with a sharp point at its rear corner, leaving said cutting edge inclining outwardly.

4. A bit of the character described comprising a body that is polygonal in cross-section and which is curved on a radius that is diagonal of said body, and said body having a beveled wall inclining from one side to the other and extending from the inner corner of the bit to the diagonally opposite corner on an inclined plane and intersecting the wall between the outer and rear corners.

5. A bit of the character described comprising a body that is polygonal in cross-section and which is curved on a radius that is diagonal of said body, and said body having a beveled wall inclining from one side to the other and extending from the inner corner of the bit to the diagonally opposite corner on an inclined plane and intersecting the wall between the outer and rear corners on an inclined plane, leaving a sharp forwardly extended point at one of said last named corners.

6. In a mining drill, a head having two sockets with their walls intersecting radii of the body at relatively considerable angles and each having two side walls and two converging walls at each

end forming corners, polygonal bits extending into the ends of said sockets and having corners seated in the corners of said sockets and being bent and curved forwardly diagonally of the body 5 of said bits and having sharp cutting edges on their outer ends, and wedges detachably holding said bits in said sockets.

7. In a mining drill, a head having two sockets of substantially equal width with their forward 10 walls approximately radial in the body of the head and each having two converging walls at each end forming corners, polygonal bits mounted in said sockets and having corners seated in said first named corners, and being curved forwardly 15 diagonally of the bodies of said bits, and wedges clamping said bits in said sockets and extending rearwardly beyond the ends of said sockets.

8. In a mining drill, a head having a pair of sockets in the forward end thereof, bits that are

polygonal in cross-section extending into said sockets and being curved forwardly diagonally of the bodies of said bits, and sharp cutting edges on the forward ends of said bits extending from their outer corners to inwardly adjacent corners. 5

9. In a mining drill, a head having a pair of sockets in its forward end, a pair of polygonal bits extending into each of said sockets and diverging forwardly and being curved forwardly diagonally of the bodies thereof and having sharp 10 cutting edges on their forward ends extending from their outer corners to inwardly adjacent corners, and wedges having sockets in their inner and outer sides extending into said respective sockets in said head and clamping said bits in 15 said sockets in said head in forwardly diverging relationship.

end forming corners, polygonal bits extending into the ends of said sockets and having corners seated in the corners of said sockets and being bent and curved forwardly diagonally of the body 5 of said bits and having sharp cutting edges on their outer ends, and wedges detachably holding said bits in said sockets.

7. In a mining drill, a head having two sockets of substantially equal width with their forward 10 walls approximately radial in the body of the head and each having two converging walls at each end forming corners, polygonal bits mounted in said sockets and having corners seated in said first named corners, and being curved forwardly 15 diagonally of the bodies of said bits, and wedges clamping said bits in said sockets and extending rearwardly beyond the ends of said sockets.

8. In a mining drill, a head having a pair of sockets in the forward end thereof, bits that are

polygonal in cross-section extending into said sockets and being curved forwardly diagonally of the bodies of said bits, and sharp cutting edges on the forward ends of said bits extending from their outer corners to inwardly adjacent corners. 5

9. In a mining drill, a head having a pair of sockets in its forward end, a pair of polygonal bits extending into each of said sockets and diverging forwardly and being curved forwardly diagonally of the bodies thereof and having sharp 10 cutting edges on their forward ends extending from their outer corners to inwardly adjacent corners, and wedges having sockets in their inner and outer sides extending into said respective sockets in said head and clamping said bits in 15 said sockets in said head in forwardly diverging relationship.
